CAR DOOR

Wilfred A. Beauchamp, Chicago, Ill., assignor to
 The Youngstown Steel Door Company, Cleve-
 land, Ohio, a corporation of Ohio

Application August 9, 1945, Serial No. 609,799

6 Claims. (Cl. 20—26)

1

This invention relates to car doors and particularly to weatherproofing the lower edge of sliding car doors.

It is an object of this invention to provide a weathertight construction for the lower edge of sliding car doors which shall be independent of the normal variations and irregularities occurring in the car and door constructions.

A further object is to provide a weathertight construction for sliding car doors which shall be fool-proof in its establishment and provide direct contact between the weatherproofing members and the bottom edge of the doors.

A further object is to provide a weathertight construction for sliding car doors which shall be maintained regardless of subsequent deflection of the car underframe or door supporting structure.

A further object is to provide weathertight construction for sliding car doors which shall prevent lodgment of debris and secure proper weathertightness.

A further object is to provide a weathertight construction for sliding car doors of the lift type, a portion of which lies between a supporting track for the doors and the car and below the track.

Other objects of the invention will become clear as the description thereof proceeds.

In the drawings forming part of this specification:

Fig. 1 is a fragmentary elevation of a sliding lift car door with which the instant invention is utilized.

Fig. 2 is a vertical section taken on line 2—2 of Fig. 1.

Fig. 3 is a vertical section taken on line 3—3 of Fig. 2 a portion being broken away to show the relationship between the weatherproofing member and one of the track brackets.

Fig. 4 is a vertical section similar to Fig. 2 showing a modified form of the invention.

Fig. 5 is a view similar to Fig. 2 showing the door in raised position.

Referring first to the embodiment of the invention illustrated in Figs. 1, 2, 3 and 5 of the drawings, the reference numeral 10 designates a sliding car door of the lift type which is adapted to close a door opening 11 formed in each side of a railway house car. The car, as is usual in such structures, embodies a floor 12 supported along each side by means of a side sill 13 which is angular in section and which is reinforced by means of a bulb angle 14. The outer portion of the floor 12 is protected by means of a threshold plate 15 provided with a depending flange 16 ex-

2

tending downwardly below the door opening. The portion of the threshold plate 15 which projects outwardly beyond the side sill 13 is supported from the side sill through the medium of an angle 17.

A track 18 is utilized to support the door frictionally in lowered position as shown in Fig. 2 of the drawings and upon the rollers 19—19 of a lifting mechanism designated in its entirety by 10 the reference numeral 20 in raised position as shown in Fig. 5 of the drawings. The track 18 is supported in outwardly spaced relationship to the door opening 11 and depending flange 16 of the threshold plate 15 by means of a plurality of brackets 21 secured to the side sill reinforcement 14 as by means of rivets 22. The door 10 is formed with a depending flange 23 which lies below the track and when the door is in closed position between the track and depending flange 20 16 of the threshold plate.

The instant invention provides effective means for weather-proofing the lower edge of the door thereby preventing any foreign matter from entering the car through the door opening between 25 the threshold plate and the door. In the considered embodiment of the invention this means takes the form of a substantially Z-shaped weatherproofing member 24 which is adapted to close the space between the door and the depending flange of the threshold plate. To this end the Z-shaped member embodies an upstanding flange 25 so disposed as to abut the inner face of the depending flange 16 of the threshold plate, an outwardly extending downwardly inclined flange 26 which abuts the lower edge of the depending flange 23 of the door 10 and sheds debris falling thereon and a depending flange 27 which is secured to the track brackets 21 as by means of welding. As shown, the depending flange 27 of the weatherproofing member 24 is formed with a plurality of recesses 28 into which the track brackets 21 extend for securement to this flange. This construction is more clearly shown in Fig. 3 of the drawings from which it will be apparent that the recesses 28 permit both horizontal and vertical adjustment of the weatherproofing member 24 so as to insure contact with the lower edge of door flange 23.

It will be apparent from the foregoing that 50 accurate application of the weatherproofing member 24 may be obtained regardless of any discrepancies or irregularities in the door structure, car construction or in the relationship thereto of the track. This follows from the fact 55 that the stated relationship between the depend-

ing flange of the threshold plate and the lower edge of the door flange 23 is obtained after the door has been moved to its closed position and is frictionally supported upon the track. Moreover, in view of the fact that the weatherproofing member 24 is supported upon the track brackets 21, its relationship with the threshold plate and the door will not be disturbed in the event of the deflection of the side sill or side sill reinforcement or of the door track since such deflection will be accompanied by a corresponding deflection of the door and the weatherproofing member.

The embodiment of the invention illustrated in Fig. 4 of the drawings utilizes an angle weatherproofing member 29 and somewhat modified track brackets 30. Each of these brackets is formed with a horizontal portion 31 which provides a seat for the horizontal outwardly extending flange 32 of the weatherproofing member. The latter when assembled in weatherproofing relationship with the threshold plate and the door is disposed so that its upstanding flange 33 abuts the inner face of depending flange 16 of the threshold plate and its outwardly extending flange 31 abuts the edge of door flange 23. The weatherproofing member 29 is secured upon the brackets 30 as by means of welding. Vertical adjustment of this member is secured merely by raising the member relative to the track brackets and filling in any space between flange 32 and horizontal portions 31 of the track brackets by welding material. In this embodiment the depending flange 27 of the weatherproofing member 24 and the recesses formed therein are eliminated.

It will be apparent that numerous changes and modifications in the details of the invention will be clear to those skilled in the art. It is intended, therefore, that all such modifications and changes be comprehended within this invention, which is to be limited only by the scope of the claims appended hereto.

I claim:

1. In a railway house car having a door opening, a threshold plate in said door opening having a depending flange, a door track, brackets secured to said car and supporting said track in spaced relation to said flange, a sliding lift door adapted to be frictionally supported by said track, a flange on said door extending below said track and between said track and said threshold plate flange, and a weatherproofing member secured to said brackets, said member having an upstanding flange abutting the inner face of said threshold plate flange and a flange extending outwardly and abutting the edge of said door flange when said door is frictionally supported, the upper edge of said upstanding flange of said member lying below the upper edge of said threshold plate flange, the lower edge of said latter flange lying above said outwardly extending flange of said member whereby said member may be adjusted vertically to contact the lower edge of said door flange when said door is frictionally supported.

2. In a railway house car having a door opening, a threshold plate in said door opening having a depending flange, a door track, brackets secured to said car and supporting said track in spaced relation to said flange, a sliding lift door adapted to be frictionally supported by said track, a flange on said door extending below said track and between said track and said threshold plate flange, and a weatherproofing member secured to said brackets, said member having an upstanding flange abutting the inner face of said

threshold plate flange and a flange extending outwardly and abutting the edge of said door flange when said door is frictionally supported, said outwardly extending flange being inclined downwardly, the upper edge of said upstanding flange of said member lying below the upper edge of said threshold plate flange, the lower edge of said latter flange lying above said outwardly extending flange of said member whereby said member may be adjusted vertically to contact the lower edge of said door flange when said door is frictionally supported.

3. In a railway house car having a door opening, a threshold plate in said door opening having a depending flange, a door track, brackets secured to said car and supporting said track in spaced relation to said flange, a sliding lift door adapted to be frictionally supported by said track, a flange on said door extending below said track and between said track and said threshold plate flange, and a weatherproofing member secured to said brackets, said member having an upstanding flange abutting the inner face of said threshold plate flange, a flange extending outwardly and abutting the edge of said door flange when said door is frictionally supported, and a depending flange, the latter flange being secured to said track brackets the upper edge of said upstanding flange of said member lying below the upper edge of said threshold plate flange, the lower edge of said latter flange lying above said outwardly extending flange of said member whereby said member may be adjusted vertically to contact the lower edge of said door flange when said door is frictionally supported.

4. In a railway house car having a door opening, a threshold plate in said door opening having a depending flange, a door track, brackets secured to said car and supporting said track in spaced relation to said flange, a sliding lift door adapted to be frictionally supported by said track, a flange on said door extending below said track and between said track and said threshold plate flange, and a weatherproofing member secured to said brackets, said member having an upstanding flange abutting the inner face of said threshold plate flange, a flange extending outwardly and abutting the edge of said door flange when said door is frictionally supported, and a depending flange, recesses formed in said latter flange, said brackets extending into said recesses and being secured therein to said latter flange the upper edge of said upstanding flange of said member lying below the upper edge of said threshold plate flange, the lower edge of said latter flange lying above said outwardly extending flange of said member whereby said member may be adjusted vertically to contact the lower edge of said door flange when said door is frictionally supported.

5. In a railway house car having a door opening, a door track carried by said car in spaced relation to said door opening, a sliding lift door adapted to be frictionally supported by said track in spaced relation to said door opening, a flange on said door extending below said track and between said track and said door opening, and a weatherproofing member carried by said car, said member abutting a member on said car below said door opening and extending outwardly across the space between said door and said door opening and abutting the edge of said door flange when said door is frictionally supported, said weatherproofing member lying below the upper edge of said car member, the outwardly extending portion of said weatherproofing member lying

below the lower edge of said car member whereby said weatherproofing member may be adjusted vertically to contact the lower edge of said door flange when said door is frictionally supported.

6. In a railway house car having a door opening, a door track carried by said car in spaced relation to said door opening, a sliding lift door adapted to be frictionally supported by said track in spaced relation to said door opening, a flange on said door extending below said track and between said track and said door opening, and a weatherproofing member carried by said car, said member abutting a member on said car below said door opening and extending downwardly and outwardly across the space between said door and said door opening and abutting the edge of said door flange when said door is frictionally supported, said weatherproofing member lying below the upper edge of said car member, the out-

wardly extending portion of said weatherproofing member lying below the lower edge of said car member whereby said weatherproofing member may be adjusted vertically to contact the lower edge of said door flange when said door is frictionally supported.
